UNITED STATES PATENT OFFICE.

FLETCHER HARRIS DOUB, OF ALAMEDA, CALIFORNIA, ASSIGNOR TO GOSWADO MFG. COMPANY, OF ALAMEDA, CALIFORNIA, A CORPORATION OF CALIFORNIA.

METHOD OF MAKING HATS.

Application filed August 3, 1920, Serial No. 400,959. Renewed March 20, 1922. Serial No. 545,346.

To all whom it may concern:

Be it known that I, FLETCHER HARRIS DOUB, a citizen of the United States, and a resident of Alameda, county of Alameda, State of California, have invented new and useful Methods of Making Hats, of which the following is a specification.

The present invention relates to hats or head coverings to be worn upon the person, and has reference more particularly to an improved art or method of producing same.

In the accompanying drawing Figure 1 is a perspective view of two bundles of fiber from which the hat is produced. Figure 2 is a plan view of one of the bundles arranged in fan-like formation with stitches intermediate its ends. Figure 3 is a plan view of the center of the fiber bundle shown in Figure 2 with the middle of the same cut out within the stitching and with the strands of the fiber divided in two groups. Figure 4 is a plan view showing the second bundle arranged across the bundle shown in Figure 3. Figure 5 is a plan view showing the fibers of both bundles worked out so that they represent a round blank with all of the fibers radiating from a common center and Figure 6 is a perspective view of a completed hat.

As a basis of illustrating the salient features of the invention I will confine the description to the preferred material used, i. e., vegetable fiber, and one method of working or arranging the fiber in producing a lady's hat of more or less conventional shape.

The different figures in the accompanying drawing are arranged to represent the important progressive steps which are carried out during the preferred method of making a hat. The first important step in the method consists in arranging one of the bundles of fiber 5 and 6, shown in perspective in Figure 1, in a substantially fan like formation as in Figure 2 with the middle thereof drawn together by the stitched oval or circular series of the threads 7. The center of the oval, or circle as the case may be, thus produced may then be cut out to provide an opening as at 8, see Figure 3. In

stead of this step to produce the opening 8 the bundle 5 may be cut in two with the ends joined by the stitched threads 7; at any

rate the particular means of producing the opening 8 is immaterial so long as the same exists and with the fiber radiating from around the same, as in Figure 3, with one of the bundles thus fixed, the other bundles designated as 6 will then be stitched transversely across the first named bundle as in Figure 4 and with the fiber thereof likewise arranged substantially fan shape. With the two bundles arranged substantially as shown in Figure 4 the strands of the fiber in each will be worked around so that they will radiate from practically a common center and at the same time additional stitches are taken around the prearranged strands with the first series 7 thereof comprising the center. The texture of the worked strands may if desired gradually thin out to provide a fringed brim as at 9.

The shaping of the hat may be accomplished at any convenient time, for instance when the method is being carried out or after the formation of the general shaping of the hat.

I have found in practice that a hat made substantially in accordance with the present method, especially if vegetable or the like fiber is used, is capable of withstanding the most severe use without impairing its shape or in any otherwise destroying its appearance. Furthermore the time and expense required in producing the finished article is much less than that incurred in the present known methods. There is also to be considered the advantages to be gained in arranging the strands of material radially of the hat rather than the heretofore accepted form of weaving or braiding them circumferentially around the same. The resistance to breaking and becoming out of shape is due primarily to the peculiar arrangement of the strands and the means for joining the same together.

In the first instance the fiber or other material is carefully combed out and weighed in bundles of such sizes and lengths according to the shape and size of the hat to be produced.

I claim:

1. The herein described method of producing hats from fiber or the like strands which consists in grouping two measured

quantities of the fiber with their lengths arranged crosswise to each other, joining the quantities at the point of intersection, working the strands of each quantity in to a substantially circular formation, and maintaining the same in such form by a circular series of stitches.

2. The method of producing hats from fiber or the like strands as set forth in claim 1, and in which one of the quantities is provided with an opening intermediate its ends and around which the circular series of stitches extend circumferentially of the hat.

FLETCHER HARRIS DOUB.
